UNITED STATES PATENT OFFICE

150,019

DESIGN FOR A ROLY-POLY TOY OR THE LIKE

Thomas C. Martin, Natick, Mass.

Application May 24, 1947, Serial No. 139,255

Term of patent 14 years

(Cl. D34—4)

To all whom it may concern:

Be it known that I, Thomas C. Martin, a citizen of the United States, residing in Natick, in the county of Middlesex and State of Massachusetts, have invented a new, original, and ornamental Design for a Roly-Poly Toy or the like, of which the following is a specification, reference being had to the accompanying drawing, forming a part thereof, in which

Figure 1 is a front view of the roly-poly toy or the like showing my new design.

Figure 2 is a back view, and,

Figure 3 is a side view thereof.

I claim:

The ornamental design for a roly-poly toy or the like, as shown.

THOMAS C. MARTIN.
